ROBERT F. INGERSOLL, DECEASED, BY JESSIE B. INGERSOLL, SPECIAL ADMINISTRATRIX, OF KELLOGG, IDAHO, ASSIGNOR TO T. S. INGERSOLL, OF SAN FRANCISCO, CALIFORNIA.

AUTO-LOCK.

1,380,478.

Specification of Letters Patent. Patented June 7, 1921.

Application filed March 22, 1920. Serial No. 367,798.

To all whom it may concern:

Be it known that I, JESSIE B. INGERSOLL, a citizen of the United States, residing at Kellogg, in the county of Shoshone and State 5 of Idaho, and who is administratrix of the deceased ROBERT F. INGERSOLL, who did invent new and useful Improvements in Auto-Locks, of which the following is a specification.

10 This invention relates to improvements in auto locks of that character in which the automobile is locked against operation under its own power but is free to be shifted or moved about in case of fire or other accidents. The invention also relates to improvements in that class of auto locks wherein reliance is placed upon rendering the spark circuit inoperative in order to lock the machine.

15 It is one of the objects of this invention to so correlate the auto lock with a combination lock mechanism that one will coact with the other in circuit closing and circuit positions with a view of rendering mutual locking co-25 operation.

20 It is a further object of this invention to dispose circuit closing means and also a portion of the combination lock mechanism in a closed casing, preferably located on the 30 hood side of the dash, all of the mechanism in said casing or housing being not only inaccessible when the hood is closed, but also inaccessible when the hood is opened. In this connection, a further feature of novelty 35 consists in providing combination lock mechanism wherein the combination may be altered at will, there being a novel pick-up means disposed in said housing to pick-up any new combination.

40 It is a feature of novelty of this invention to dispose the dial of the combination lock mechanism on the seat side of the dash and to then extend through the dial and tumbler portions of the combination lock mechanism 45 an operating stem whereby circuit closing means may be operated on the seat side of the dash in predetermined relation with respect to the operation of the combination lock mechanism.

50 The invention has many other objects and features which will be more fully described in connection with the accompanying drawings and which will be more particularly pointed out in and by the appended claims.

In the drawings:—

55 Figure 1 is a front elevation of the dash looking from the seat side and showing the dial of the combination lock mechanism.

Fig. 2 is a view in elevation looking from the hood side and showing the circuit closing means in a circuit closing position.

Fig. 3 is a view similar to Fig. 2 showing the circuit closing means in a circuit opening position.

Fig. 4 is a horizontal sectional view on line 4—4 of Fig. 2 with the circuit closing means in a circuit closing position.

Fig. 5 is a view similar to Fig. 4 with the circuit closing means in a circuit opening position.

70 Fig. 6 is a vertical sectional view on line 6—6 of Fig. 5.

Fig. 7 is a fragmentary sectional view on line 7—7 of Fig. 2.

Fig. 8 is a sectional view on line 8—8 of Fig. 6.

Fig. 9 is a sectional view on line 9—9 of Fig. 6.

Like characters of reference designate 80 similar parts throughout the different figures of the drawings.

As illustrated, 1 designates the dash of an automobile, the seat side being indicated at 2, and the hood side at 3. The engine is 85 diagrammatically shown at 4 and a source of current is designated at 5. A spark circuit comprises conductors 6, 7 and 8, conductors 6 and 8 being electrically connected to terminals 9 and 10 which will be hereinafter specifically described.

90 On the seat side of the dash is suitably secured a mounting 11 for a combination lock dial 12, the latter being rotatable by means of a knurled finger grip 13. The dial 12 is suitably graduated, as clearly shown in Fig. 1, and the mounting 11 is provided with an index 14 with which the graduations will be brought into registry in the usual manner of operating a combination lock. Secured to the dial 12 and extending through and being journaled in the mounting 11, is a sleeve 15 which extends through the dash as shown particularly in Fig. 6. On the sleeve 15 are loosely mounted tumblers, preferably in the form of disks 16 and 17 having notches 18 and 19. A tumbler disk 20 is fixed on sleeve 15 and is provided with a notch 21. Tumbler disk 20 is provided with teeth 22.

adapted to mesh with teeth 23, formed on sleeve 15, whereby disk 20 may be changed in its position with respect to sleeve 15 when it is desired to change the combination. A 5 spring slip device 24 serves to hold the disk 20 in position, as will be seen more particularly by reference to Fig. 6. The disks 16, 17 and 20 are provided with co-acting advancing combination lugs 25, 26, 27 and 28, 10 as will be seen more particularly by reference to Fig. 5.

Reference will next be made to the terminals 9 and 10, as regards their specific construction. A housing 29, having an 15 open end 30, is suitably fastened upon the hood side 3 of the dash 1, for the purpose of inclosing the mechanism of my invention. Tubular projections 31 and 32 are suitably secured at diametrically opposite points on 20 periphery of said housing and projecting laterally therefrom. Internally, said tubular projections are suitably insulated for projection therethrough of conductors 6 and 8 for the purpose of connecting said conductors 6 and 8 with the terminals 9 and 10, respectively. Terminal contacts 9 and 10 are 25 suitably insulated by insulating material 33 and 34, from the housing 29. Contact terminal 9 comprises a base portion 35 which is secured to the housing 29, and which is provided with an angularly disposed portion 36 having a contact face 37. A locking portion or groove 38 is disposed in said contact face. Said terminal 9 is provided 30 with a ledge stop 39, as will be seen more particularly in Figs. 5 and 7. Terminal 10 is identical with terminal 9 except for the omission of the stop ledge, said terminal having a base portion 40, secured to the 35 housing 29, and an angle portion 41 providing a contact face 42, and in which contact face is formed a locking groove 43.

A reciprocable and rotatable circuit closing means is provided for co-action with 40 said terminals for closing circuit to render said spark circuit operative, or opening circuit to render the spark mechanism inoperative.

As illustrated, said circuit closing means 45 includes a bar of electrically conducting material, as indicated at 44, said bar having contact faces 45 and 46 for engagement with contact faces 37 and 42 of terminals 9 and 10. Said bar 44 also has locking ribs 47 and 48 for co-action with locking grooves 38 and 43 so that said bar cannot be jarred or oscillated out of circuit closing position by running vibration of the automobile, or by other accidental or incidental causes. He preferred to mount said 50 bar 44 upon a strip of insulating material 49, the latter having secured thereto an operating stem 50, for the circuit closing bar. In practice. He preferred to insert the operating stem 50 through the circuit closer, the

parts being provided with polygonal portions whereby a non-rotative mounting may be effected, a screw 51 serves to anchor the circuit closer upon the stem. Said stem 50 is rotatively and longitudinally movably 55 mounted in sleeve 15 and it extends past finger grip 13 and is provided with a knurled finger grip 52, constituting means whereby said stem may be rotatively or longitudinally actuated. Interposed between 60 the circuit closer and the inner end of sleeve 15 is a spring 53, the function of which is normally to force the circuit closer into a circuit opening position, as shown in Fig. 5, and also, to hold the ribs and grooves in 65 locking co-action when the closer is in the position shown in Fig. 4, the spring also functioning to effect efficient electrical engagement.

The circuit closer is interdependently correlated with the combination lock mechanism in such a manner that one acts to lock the other when in certain relation.

The circuit closer is provided with a finger 85 54 projecting rearwardly therefrom. This finger not only functions as a tumbler co-acting and locking member but also as a stop, and I will first describe its action as a stop. In this construction, the circuit closer only oscillates through a length of 90 travel of 90 degrees, and it is the object of the stop mechanism to limit oscillation to this extent in order that the circuit closer may be held in proper position for linear movement. A lug 55, mounted as will hereinafter be described, projects into the path of said finger 54 and limits rotative movement of the closer in a clock-wise direction. An angle stop limits movement of said closer in a contra-clockwise direction and 100 the same is provided with a longitudinal portion 56, for performing this function during linear movement of the circuit closer, said angle stop having a transversely disposed portion for restraining linear 105 movement of said closer while the same is being rotated into a circuit closing position. It will be seen by reference to Fig. 7 that the closer contacting face 58, is somewhat in the rear of the face 37 whereby the closer 110 will be held sufficiently retracted with respect to 37 to permit the locking rib 47 to ride upon said face and finally descend into groove 38. It will thus be seen that the oppositely acting stops for holding the circuit 115 closer in the position shown in Fig. 5 both permit of longitudinal movement of said closer while acting to restrain same to a linear path of movement.

I will next refer to the manner in which 120 the finger 54 co-acts with the combination mechanism.

When the circuit closer is being retracted in the vertical position shown in Fig. 6, to the left thereof, the finger 54 will pass 125

through notches 18, 19 and 21, as shown in Fig. 9, providing the disks are in an unlocked position. After the finger 54 has entered said notches then the circuit closer 5 will have reached a position with respect to angle stop 57 so that the circuit closer may be rotated into a circuit closing position, as shown in Fig. 4. The disks will partake of this rotation throughout 90 degrees and will 10 be held by the finger in an unlocked position. The importance of the feature is that the combination lock cannot be jarred out of an unlocking position, as regards the disks, by vibration of the automobile and therefore 15 when it is next desired to open the circuit, the disks will be in unlocking relation. However, if anyone of the notches 18, 19 or 21 were not in registry with finger 54, as shown in Fig. 6, then it would be impossible 20 to retract the circuit closer sufficiently to free the same from stop 56 and thus it would be necessary to set the combination into a releasing position before the circuit closer could be shifted into a circuit closing 25 position. Therefore, it will be seen that I am able to lock the circuit closer in a circuit opening position, and it will also be seen that the stops co-act with the disks to prevent rotation of the circuit closer until the 30 latter has been retracted to a predetermined position.

A closure 59 is threaded on the end of the housing and I provide a set screw 60 for locking the closure in a predetermined position. Stops 61 are secured to the closure and are disposed on opposite sides of the 35 closer, as shown in Fig. 5, to prevent rotation of the latter.

It is a primary object of this invention 40 to provide an auto lock in which no key or other device will be necessary to the user, and it is a feature of this invention to provide combination pick-up means, in the housing, for the purpose of picking up a new combination when the user desires to 45 change the combination of a lock.

I have hereinbefore described how disk 20 may be rotatively shifted on sleeve 15 to change the combination. Now my improved 50 pick-up means includes a guide 62 in which a pick-up key 63 is slidably mounted. Said key has a pick-up terminal 63 which is movable through the notches 18, 19 and 21 when the latter are in registry, a finger grip terminal 64 being provided for manipulating said key. Said key is of sufficient length so that the closure 59 cannot be completely adjusted and locked into a housing closing position until the pick-up key is fully retracted as 55 shown in Fig. 6. Therefore, irrespective of any change in the combination, this pick-up means acts as an indicator when the device is assembled or when the closure 59 is being set in place, to indicate the position of the 60 combination disks. Furthermore, when the 65

closure 59 is in position, it serves to hold the pick-up key from interfering with the disks because it is impossible for the pick-up to move with the parts in the position shown in Fig. 6. I prefer to form the stop 70 55 on the guide 62.

Assuming that the parts are in the position shown in Fig. 4, with the circuit closer in contact with the terminals 9 and 10 and the finger 54 inserted through the notches 75 and holding the disks in an unlocking position wherein it will be impossible to turn the dial 12, the operator in order to render the spark circuit inoperative, will grasp finger grip 52 and pull against spring 53 80 until the locking ribs are released from the locking grooves. Then the operator will turn grip 52 in a clock-wise direction, looking at Fig. 2, until the circuit closer is in the position shown in Fig. 3, the stop 55 limiting further movement. Then by releasing grip 52, spring 53 will reciprocate the closer into the position shown in Fig. 5 thereby withdrawing finger 54 from the combination 85 disks. Now if the operator wishes to lock the closer in the position shown in Fig. 5, he will grasp grip 13 and rotate the same slightly and this will advance at least one disk so that its notch will be out of registry with finger 54. Thereafter, it will be impossible to retract the closer into such relation to stop 58 that it can be rotated into a circuit closing position. Thus the car will be locked against operation under its own power. It will be understood that the spark 100 circuit may be rendered inoperative by merely shifting the circuit closer into the position shown in Fig. 5 without adjusting any of the disks into a locking position, but in this adjustment, the car will not be locked against operation under its own power but will be merely rendered inoperative. Assuming that the circuit closer is locked in the position shown in Fig. 5, then it will be necessary to readjust the combination lock mechanism before the circuit closer can be 105 released for retraction into a circuit closing position. After the combination has been released or unlocked, then the circuit closer may be reciprocated and then rotated back from the position shown in Fig. 5 to the 110 position shown in Fig. 4. It will now be clear that the ledge stop 9 limits rotation of the circuit closer and indicates when the user must release grip 52 in order to free 115 the closer for action by spring 53.

It will thus be seen that in a circuit closing position, my improved circuit closing means locks the combination mechanism in a releasing position by means of finger 54. 125 and thereby prevents the combination mechanism or its disks from being jarred out of a releasing position. This function is performed notwithstanding the rotative movement necessary to release the circuit 130

closer. In this relation, the combination lock mechanism is passive and the circuit closing means is active. With the parts in the position shown in Fig. 5, the circuit closing means is in circuit opening position, said means being passive.

It is believed that the utility and advantages of the invention will be clearly understood from the foregoing description, and 10 while I have herein shown and described one specific form of the invention, I do not wish to be limited thereto except for such limitations as the claims may import.

I claim:

- 15 1. A lock switch comprising a casing, permutation disks in said casing, each disk being provided with a recess, means for operating said disks to aline said recesses, diametrically opposed contacts in said casing, 20 a reciprocable and rotatable shaft concentric with said disks and operating means therefor, a crosshead carried by said shaft comprising a conducting portion insulated from the shaft, lugs on the bottom of said casing, 25 a spring normally holding said crosshead between said lugs to prevent rotation thereof and of the shaft, a lug carried by said crosshead and normally engaging said disks to prevent reciprocation of said shaft but positioned to enter said recesses when said recesses are properly alined, whereupon said shaft and crosshead may be reciprocated to

move said crosshead above the plane of said contacts, rotated to bring said crosshead directly over said contacts, and released to 35 permit said crosshead to engage said contacts.

2. In an auto lock, a housing, terminals fixed in said housing, a combination lock mechanism including tumbler disks in said 40 housing, a member for co-action with said terminals, means for locking said disks to said member, when the latter is in one position, said member and one of said terminals having co-acting portions, and a spring for 45 holding said member in co-action with said terminal to lock said member in one position thereby locking said tumblers against movement, substantially as described.

3. In an auto lock, contact terminals in 50 diametrically opposed relation, a reciprocable and rotatable bar for engagement with said terminals, and an angle guide having a longitudinal portion for guiding said bar during linear movement of the latter and a 55 transversely disposed portion for guiding said bar during rotative movement of the latter, substantially as described.

In testimony that I claim the foregoing in behalf of the deceased, I hereby affix my 60 signature.

JESSIE B. INGERSOLL,
Administratrix of Robert F. Ingersoll, deceased.
